No. 715,592.

Patented Dec. 9, 1902.

W. W. LOBDELL.

OPERATING MELTING FURNACES.

(Application filed Oct. 22, 1901.)

(No Model.)

Inventor:

William W. Lobdell

by his Attorneys

Howard & Howar

UNITED STATES PATENT OFFICE.

WILLIAM W. LOBDELL, OF WILMINGTON, DELAWARE.

OPERATING MELTING-FURNACES.

SPECIFICATION forming part of Letters Patent No. 715,592, dated December 9, 1902.

Application filed October 22, 1901. Serial No. 79,592. (No model.)

To all whom it may concern:

Be it known that I, WILLIAM W. LOBDELL, a citizen of the United States, and a resident of Wilmington, Delaware, have invented certain Improvements in Operating Melting-Furnaces, of which the following is a specification.

The object of my invention is to insure greater uniformity than usual in the operation of cupolas or other melting-furnaces provided with air-blast; and this object I attain by so treating the air intended for the blast as to deliver it to the furnace at all times under uniform or substantially uniform conditions as to its temperature and the percentage of moisture contained in it.

In the accompanying drawings, Figure 1 is a longitudinal section of one of the means which may be adopted in carrying out my invention, and Fig. 2 is a transverse section of the same.

Much difficulty is experienced by furnace-men who operate melting-furnaces, such as cupolas, which are dependent upon an air-blast, because of the variations in atmospheric conditions which sometimes take place during a single run. It frequently happens that both temperature and humidity conditions vary so greatly between the beginning and end of the run that if the furnace is charged with the proportions of fuel and metal proper to bring about the desired result under the condition of blast when the heating begins the changed atmospheric conditions before the run is ended will so affect the operation of the furnace that the metal produced is not uniform, but varies in grade, depending upon the variation in temperature and humidity of the blast. The aim of my invention, therefore, has been to so treat the air intended for the blast that its condition as to temperature and humidity when it is delivered to the furnace shall be uniform or substantially uniform at all times, uniformity of operation of the furnace being thereby effected and consequent uniformity of product insured.

One form of apparatus employed by me in carrying out my invention is that shown in

Figs. 1 and 2, on reference to which 1 represents a trough or conduit communicating at one end with an air-intake 2 and discharging at the other end into the intake-pipe 3 of a blowing-machine 4, which supplies the blast for the cupola, so that the air entering the conduit at one end of the same will be caused to flow throughout the length of the conduit before reaching the blower. Suspended in the upper portion of the conduit is a pan or receptacle 5, having a perforated bottom, this pan receiving a supply of water through a central pipe 6, so that a constant shower of water descends from the pan to the bottom of the conduit throughout substantially the entire length of the latter, the air in traversing the conduit being brought into intimate contact with these falling streams of water and the effect being that the air emerges from the conduit and enters the blower at a temperature very nearly approaching the temperature of the water and with uniform percentage of moisture. For instance, if the air at the intake is at a higher temperature than the water this temperature will be reduced, and if the air is at a lower temperature than the water such temperature will be raised, and at the same time the conditions as to percentage of humidity will likewise approach uniformity—that is to say, if the air contains vapor of water in excess of a certain amount such excess will be precipitated, the result being that variations in temperature or humidity of the air-supply are corrected, so that the air flowing from the conduit to the blowing-machine is at all times of substantially uniform character as concerns both its temperature and humidity. The water is prevented from accumulating in the conduit shown in Fig. 1 by means of a drain-pipe 13.

Having thus described my invention, I claim and desire to secure by Letters Patent—

1. The mode herein described of effecting uniformity in the operation of melting-furnaces using an air-blast, said mode consisting in passing the air for said blast in intimate contact with water, whereby it is delivered to the furnace throughout a run in a substan-

tially uniform condition as regards the percentage of moisture contained in it, substantially as described.

2. The mode herein described of effecting uniformity in the operation of melting-furnaces using an air-blast, said mode consisting in first passing the air through finely-divided streams of water, substantially as described.

In testimony whereof I have signed my name to this specification in the presence of 10 two subscribing witnesses.

WILLIAM W. LOBDELL.
